UNITED STATES PATENT OFFICE.

CHRISTOPHER M. BUCK, OF SAN LEANDRO, CALIFORNIA.

INTERNAL-COMBUSTION ENGINE.

1,199,239.

Specification of Letters Patent. Patented Sept. 26, 1916.

Application filed September 23, 1912. Serial No. 721,755.

To all whom it may concern:

Be it known that I, CHRISTOPHER M. BUCK, a citizen of the United States, and a resident of the city of San Leandro, State of California, have invented new and useful Improvements in Internal-Combustion Engines, of which the following is a specification.

This invention relates to improvements in internal combustion engines and more particularly to the ignition mechanisms thereof.

It is the general practice to provide internal combustion engines with dual electric ignition. One system derives its energy from a battery of galvanic cells operating through a coil and distributor. The other system derives its energy from a magneto geared to the engine shaft. The magneto is switched into operation after the engine is started and because of its greater efficiency and economy is depended upon for practically all of the running ignition. The battery system of ignition is used merely in starting the engine and as a reserve should the magneto fail.

It is the object of this invention to provide a simple means of throwing the distributor of the battery system out of engagement with the engine when not in use; thus saving the distributor (that is a sensitive and delicate mechanism) from the wear and tear of operation when not called upon to perform its function.

Broadly stated the invention consists of a clutch mechanism introduced in the distributor or timer shaft between the distributor and the cam shaft or other source of rotation.

In the drawing: Figure 1 is a side elevation of this invention illustrating the manner of applying it to an internal combustion engine. Fig. 2 is an enlarged detail in side elevation of the distributor, the distributor shaft and the interposed clutch mechanism.

In detail the construction consists of the driving clutch jaw 1 fixed on the distributor shaft *x* by the set screws 2. The driven clutch jaw 3 has the central bore 4 adapted to receive the end of the distributor shaft 50 projecting through the jaw 1. The clutch jaws meet on a line lateral to the diameter of the distributor shaft. The purpose of this arrangement is to make it impossible to set the clutch, except when the time shaft 55 of the engine is in the proper relative position to the distributor; if it were otherwise

the distributor might be engaged at the wrong interval and disturb the timing of the engine, that insures the delivery of the ignition spark in the cylinder under compression, in the firing cycle. This object may also be accomplished by a single notch only in one jaw engaging a single pin in the opposite jaw of the clutch, but the present form is preferred because of its simplicity and strength. The distributor can not be reclutched out of time with the timing of the engine, because the clutch cannot engage unless both jaws thereof are in the same relative positions as they were when declutched. When the distributor is declutched it will ride around on top of the clutch jaws until the proper position is reached for it to engage, and as there is but one jaw, and that is lateral to the diameter 60 of the distributor shaft it is impossible for the distributor to engage except at the proper cycle of operation, when the engine is turned over by hand or mechanical means until the distributor clutch engages and the 70 engine begins to run on its own power. The jaw 3 is provided with the diametrically reduced portion 5 upon which the distributor *y* is fixed by set screws *z*. The driven jaw 3 is provided with the annular 75 groove 6 to receive the yoke 7, having trunnions engaging the yoke 8 of the bell crank lever 9. The bell crank lever is pivoted at 10 in the bracket 11 that is adapted to be fastened to the engine near the distributor. 80 The bell crank is pivoted to the rod 12 extending to any point within convenient reach of the operator.

The spring latch 13 fixed on the bracket 11 is provided with the notches 14 and 15 95 into which the detent 16 is adapted to seat. The function of the detent and latch is to hold the clutch in the operative and inoperative positions. Other means of accomplishing the same purpose may be provided. To 100 limit the disengagement of the clutch, the set screw 17 threaded in the lug 18 on the bracket 11 is provided.

It is the usual practice to drive a distributor shaft by a miter gear enmeshed with a 105 similar gear fixed upon the cam shaft of the engine which in turn is geared to the engine shaft. The distributor consists of a series of ignition terminals corresponding in number with a multiplicity of cylinders of the 110 engine. The distributor terminal rotated by the distributor shaft causes a properly timed

igniting discharge within each cylinder served by its ignition terminal.

A distributor for high tension current as demanded in the ignition systems of internal combustion engines is an instrument of precision and delicacy subjected to constant vibration when in operation. Exposed to grit and general abusive wear and tear, it is a common experience to have the distributor fail to work properly in an emergency. With this invention interposed in the driving mechanism of the distributor, it can be declutched when the engine is running properly on the magneto system, saving all unnecessary wear and tear in the working parts of the distributor. This greatly prolongs its usefulness and gives insurance that when thrown into operation, its mechanical parts will be in the same condition as when last declutched.

Without departing from the spirit of this invention, the manner of putting it into practice may be altered by changes in mechanical detail or by locating it at different points in the actuating mechanism of the distributor.

The distributor could be operated electrically by operating the clutch by a magnet connected to the ignition battery. In this manner the distributor would be automatically engaged when the ignition switch was

thrown on, and vice versa. The simpler form of mechanically operated clutch is illustrated as best disclosing the invention which resides in the fact of throwing the distributor into and out of engagement at will.

Having thus described this invention what is claimed and desired to be secured by Letters Patent is:

1. In combination with the ignition system of internal combustion engines, a distributor shaft; an electrical distributor slideable on said shaft and provided with a clutch jaw; a clutch jaw on said shaft, said clutch jaws adapted to engage on a line lateral to the diameter of said shaft and means for clutching and declutching said distributor.

2. In combination with the ignition system of internal combustion engines, a distributor shaft, an electrical distributor slideable on said shaft and provided with a clutch jaw; a clutch jaw on said shaft, said clutch jaws adapted to engage on a line lateral to the diameter of said shaft and means for raising and lowering said distributor.

CHRISTOPHER M. BUCK.
